CONTAINER

Cesare Barbieri, New York, N. Y., assignor to
Dixie-Vortex Company, Chicago, Ill., a corpora-
tion of Delaware

Application October 5, 1936, Serial No. 104,036

1 Claim. (Cl. 229—5.6)

This invention relates to improvements in containers, and more particularly to containers of the character made of paper or some similar sufficiently economical material to warrant disposition of the container after a single usage, the invention being highly desirable in connection with paper drinking cups, ice cream cups and the like, although the invention will have other uses and purposes as will be apparent to one skilled in the art.

More specifically, the invention relates to containers of this character having flat bottoms, each container being preferably made from two initially separate blanks of material, namely, a body blank and a bottom blank which are secured together during the manufacture of the container.

In the manufacture of cups or containers made of paper or similar material, one of the major items of expense is the stock used. Consequently, with economy in manufacture being an essential in this line of endeavor, it is desirable to eliminate wastage of stock, and to use as little stock as possible in keeping with the manufacture of a satisfactory and efficient product. Usually, in the manufacture of flat bottom cups or containers, such as ice cream cups, drinking cups and the like, a slightly heavier stock is used than is the case with conical or envelope containers. Accordingly, the importance of using as little stock as possible with flat bottom containers is greatly magnified.

With the foregoing in mind, it is an important object of the present invention to provide a flat bottom container made of paper or similar material in which a very material saving of stock is effected without detracting in any manner from the efficiency and serviceability of the container.

Another object of this invention is to provide a flat bottom container made of a plurality of initially separate blanks of stock, in which considerably less stock is used than is the case with containers of similar types heretofore known.

It is also an object of this invention to provide a container made of a plurality of initially separate blanks wherein less stock is used than is the case with containers of similar types heretofore known, without any lessening of the capacity of the resultant container.

Also a feature of the invention is the provision of a new and novel method of making a container of the character described.

While some of the more salient features, characteristics and advantages of the present invention have been above pointed out, others will be

come apparent from the following disclosures, taken in conjunction with the accompanying drawing, in which:

Figure 1 is a central vertical sectional view of a flat bottom container embodying principles of the present invention;

Figure 2 is a top plan view of the container seen in Figure 1;

Figure 3 is a reduced plan view of the body blank for the container prior to its formation into the container body;

Figure 4 is a fragmentary enlargement of the lower right hand portion of Figure 1;

Figure 5 is a fragmentary vertical sectional view, illustrating a slightly different form of construction; and

Figure 6 is a fragmentary vertical sectional view, illustrating a still different form of construction.

As shown on the drawing:

For purposes of illustration, I have selected an embodiment of the present invention in the form of a flat bottom paper drinking cup, or ice cream cup, of a character which is usually disposed of after a single usage, although it will be apparent that the invention is not limited strictly to the illustrated container, but may include containers for other purposes.

The illustrated container or drinking cup includes a body portion 7, which may be of truncated conical shape as illustrated, having a curled drinking rim 8 at the mouth end thereof. The opposite end of the tubular body portion 7 is closed by a bottom member 9 having a depending flange 10 which is, in this instance, adhesively attached to the lower part of the body, as indicated at 11. The lower margin 12 of the body portion, which is preferably free from adhesive, is then turned inwardly to embrace the lower margin of the flange 10, as seen clearly in Figures 1 and 4. It will be distinctly noted that the turned margin 12 terminates a very material distance below the bottom proper 9, and the annular space between the end of the turned margin 12 and the bottom proper 9 represents the amount of paper stock saved in the manufacture of this container.

The body portion of the container is made from a blank 1a shown in Figure 3. This blank, prior to its formation into the container body, is preferably provided with a suitable adhesive 13 along one of the side margins of the blank and another application 14 of adhesive is provided along the bottom margin of the blank. It will be noted from the showing in Figure 3 that the application of adhesive 14 is occurring above the

lower edge of the blank, leaving a margin 12a preferably free from adhesive which, in the completed container, is the turned margin 12 mentioned above.

- 5 In the making of the container, the body blank 1a is first cut to size and provided with the adhesive portions 13 and 14 as above described. This blank is then formed into a tubular body portion with the adhesive 13 uniting overlapped 10 marginal portions, as indicated at 15 in Figure 2 to maintain the body 7 of the container in proper shape. Either during the formation of the blank 1a into the tubular body or thereafter as 15 may be deemed most feasible, the bottom member 9 is placed in position sufficiently far inside the tube so that the adhesive 14 will unite the flange 10 of the bottom member and the container body. If so desired, a slight ironing or pressing action may be provided to insure the proper adhesion. 20 The next operation is to turn inwardly the non-adhesive margin 12a of the blank to provide the turned margin 12 of the container. This latter operation not only effects a better union between the container body and the bottom member, but 25 also provides a relatively smooth base for the container as a whole.

In containers of this type as they were usually manufactured heretofore, the adhesive 14 was brought substantially to the lower edge of the 30 blank, which blank was longer than that illustrated herein. When the bottom margin of the blank was turned inwardly, this margin extended substantially to the bottom proper 9 and was adhesively secured to the inner face of the flange 35 10, necessitating in most instances an ironing operation to insure the proper adhesion. It will be noted that the efficiency and satisfactory operation of the present container is not detracted from in any material degree by the terminating 40 of the flange 12 a relatively considerable distance below the bottom proper 9, thus saving that amount of paper stock, and by not adhesively uniting the turned margin 12 to the inner 45 face of the flange 10, although, if so desired, such adhesive union could be readily effected in the present invention. When quantity manufacture is considered, it will at once be apparent that the saving of stock effected by the present invention is a very substantial item.

50 In Figure 5, I have shown a slightly modified form of construction which results in a still greater saving of stock. In this instance, substantially the same container body is provided, but this body is slightly shorter than as previously described. The bottom member 9 with its flange 10 is adhesively secured to the body in the same manner as indicated at 11. However, the lower marginal portion of the body 55 is slightly rolled inwardly as indicated at 16, and

the lower margin of the flange 10 is also rolled slightly inwardly as indicated at 17, concentrically with the margin 16. The rolling action provides a relatively smooth base for the container as a whole and also adds to the bond 5 between the body and bottom, but it will be noted that when the slight roll is used, less body material is necessary than with the construction previously described.

In Figure 6, I have shown a construction which 10 effects a still greater saving of stock. The bottom member, together with its flange, is joined to the body in the manner above described. In this instance, however, a lower marginal portion 18 of the body is merely turned inwardly so as 15 to overlie the lower edge of the flange 10 on the bottom member and, in this instance, the turned margin 18 effects little or no engagement with any but the direct lower edge of the flange. Accordingly, the turned margin 18 need not be 20 quite as long as the margin 16 just previously described.

From the foregoing, it will be apparent that I have provided a highly efficient and satisfactory container which results, in its manufacture, in a material saving of stock, without any 25 detraction from the efficiency of the container or any lessening of its capacity. It will also be noted that a container manufactured in accordance with the principles of this invention 30 and in accordance with the novel method set forth herein eliminates certain expensive manufacturing operations, and the making of the container may be accomplished with great facility and in an economical manner.

35 I am aware that many changes may be made and numerous details of construction may be varied through a wide range without departing from the principles of this invention, and I, therefore, do not purpose limiting the patent 40 granted hereon otherwise than is necessitated by the prior art.

45 I claim as my invention:

A container of the character described made from a body blank and a bottom blank, the body blank having adhesive adjacent a side edge to join overlapping marginal portions to provide a tubular body, and said body blank having adhesive along the bottom edge but spaced from this edge to leave an edge part free of adhesive, 50 a bottom blank having a depending flange disposed in the tubular body with the second said adhesive joining the body and flange, and the lower body edge free from adhesive being turned inwardly so as to be crimped against the edge 55 of said flange and the extremity thereof terminating beyond said crimped engagement and a material distance below the bottom proper.

CESARE BARBIERI.
